PICKS AND LIKE TOOLS

John C. Roche, Battle Creek, Mich., assignor of
one-half to Dorene J. Zahanian, Battle Creek,
Mich.

Application August 22, 1945, Serial No. 611,960

2 Claims. (Cl. 306—32)

1

This invention relates to improvements in picks and like tools.

In tools of the pick and grub hoe type the tool head receiving end of the handle or helve is tapered inwardly, the tool head being provided with a socket having a correspondingly shaped inward taper. Such tools are subjected to very severe uses and stresses in use and are subject to severe weather conditions, with the result that the head frequently becomes loosened and may slide toward the grip end of the handle and quite frequently workmen are injured.

The main object of this invention is to provide in a tool of this character a structure in which the tool head is firmly anchored to the handle and cannot slide on the handle to the possible injury of the workman.

Objects relating to details and economies of the invention will definitely appear from the description to follow. The invention is defined in the claims.

A structure which embodies the features of the invention is clearly illustrated in the accompanying drawing, in which:

Fig. 1 is a side elevation of a pick embodying the invention.

Fig. 2 is an enlarged fragmentary view partially in section on line 2—2 of Fig. 1.

Fig. 3 is a perspective view of the head fastener of this invention.

In the accompanying drawing I have illustrated my invention as applied to a pick but it will be understood that it is desirable for use in grub hoes and like tools. These tools are subjected to very heavy strains in use, being frequently used to pry objects from the ground or heavy blocks of material such, for example, as in breaking up and removing a concrete paving slab or other type of pavement. Since stresses tend to pull the head of the tool from the handle, the handle 1 is provided with an inwardly tapered tool head receiving end portion 2 of flattened section. The tool head 3 illustrated is of the double bit pick type and is provided with an inwardly tapered socket 4 of flattened section fittingly engaging the handle end portion 2. The end portion 2 of the handle has a longitudinal groove 5 therein preferably extending somewhat above the inner edge 6 of the handle socket.

The fastener member 7 comprises a shaft portion 8 of a length exceeding the length of the head socket and terminating at its outer end in an inturned end 9 which laps the end of the handle. The inturned end terminates in a prong

2

10 which is driven longitudinally into the end of the handle. The shaft is disposed in the groove but the groove is of such depth relative to the thickness of the shaft that there is a wedging engagement between the shaft and handle and the socket when the parts are in assembled relation. The end of the fastener is bent outwardly and clamped over the inner edge of the head socket to provide a retaining hook 12.

10 In assembling, the fastener member may be placed in position with its prong driven into the end of the handle and its shaft disposed within the groove. The head is then slipped over the handle and over the fastener element and firmly 15 driven upon the inwardly tapered head receiving end portion of the handle. This may commonly be done by blows on the head end of the handle or resulting from striking the end against a suitable surface. When the head is firmly positioned the end of the fastener is bent over and clamped upon the upper edge of the head socket

To facilitate the bending and also to provide a sharp edge the inner edge of the upper end 25 of the shaft is beveled at 11 and this becomes the outer edge when it is clamped into position. The prong 10 serves to support the fastener while the head is being assembled therewith and also serves to anchor the laterally turned end 30 9 and prevent its being displaced or bent outwardly when the tool is in use. The fastener may be assembled by driving its shaft into the socket with the handle assembled therewith. That may be desirable when the device is applied to old tools.

35 I have illustrated my invention as applied to a pick but there are other tools such as grub hoes, mattocks and the like in which the invention may be embodied. It is believed this disclosure will enable those skilled in the art to embody or adapt the invention as may be desired.

Having thus described my invention what I claim as new and desire to secure by Letters Patent is:

40 1. In a fastener for tool heads, a handle having an inwardly tapered tool head-engaging end substantially ovate in cross-section providing flattened sides, one of the flattened sides having 45 a relatively wide groove therein with a flat bottom wall, a tool head having an inwardly tapering socket of a shape in cross-section to mate with the tapering end of said handle, the groove being of greater length than the length of the 50 tool head socket, and a fastener for anchoring

the tool head on the handle including a bar rectangular in cross-section of substantially the same width of the groove and of a thickness greater than the depth of the groove to provide wedging engagement between the tool head and handle, the outer end of the bar being reversely angularly bent to provide a terminal prong adapted to be driven into the outer end of the handle and the inner end of the bar adapted to be bent away from the handle and into U-shape for overlying the flattened side wall of the tool head.

2. A fastener as in claim 1, wherein the inner end of the bar is bevelled to facilitate prying of said end from the groove in the handle for bending around the side of the tool head.

JOHN C. ROCHE.
